UNITED STATES PATENT OFFICE

CLARENCE B. HARBISON, OF LIMA, OHIO, ASSIGNOR TO THE OHIO STEEL FOUNDRY COMPANY, OF LIMA, OHIO, A CORPORATION OF OHIO

SIDE FRAME

Application filed May 18, 1931. Serial No. 538,097.

This invention relates to improvements in railway trucks of the type including a side frame and bolster, and has for its principal object to provide an improved construction 5 of trucks of the character described, wherein room is provided for a relatively large number of springs between the bolster and the spring plank, with means on said spring plank providing maximum strength and support for the springs, but permitting ready access thereto for removal.

A further object of the invention is to provide an improved arrangement for strengthening the side frame adjacent the spring plank.

Other objects of the invention will appear from time to time as the description proceeds.

The invention may best be understood by reference to the accompanying drawing, in which

Figure 1 is a fragmentary side view of a side frame and bolster constructed in accordance with my invention.

Figure 2 is a detail section taken on line 25 2-2 of Figure 1.

Figure 3 is a detail section taken on line 3-3 of Figure 1, with parts broken away.

Referring to details of the embodiment of my invention shown in the drawing, a truck 30 side frame is indicated generally at 10 and comprises a compression member 11, tension member 12 and vertical columns 13, 13. A bolster is indicated generally at 14, the end of which extends between the columns 13, 13.

The portions of the tension member 12 between the columns 13, 13 are flanged laterally at 16, 16 to form a widened base for the spring plank 15 and the springs mounted thereon. The frame is strengthened by reinforcing 40 angle ribs 17, 17 formed at the inner and outer meeting corners of the columns 13 and the flanged extensions 16, as clearly shown in the several figures.

The spring plank 15 is made wider at the longitudinal center line of the side frame so as to accommodate three springs 21, 21, 21 arranged in alignment between the upright columns 13, 13. Two pairs of springs 22, 22 and 23, 23 are arranged on the inside and outside of the center springs 21 on the nar-

rowed portions of the spring plank. Said spring plank is provided with upstanding flanges 24, 24 along the main body thereof, said flanges extending continuously at a uniform height to the point where the spring 55 plank enters the columns 13, 13 between the inner angle ribs 17, 17 and from thence said flanges are decreased in height to a point at the sides of the center springs 21, 21, 21, as indicated at 24a. This permits the spring 60 plank and its flanges to be formed from a sheet of metal of uniform width. Beyond said center springs the side flanges are omitted and the margins of the plank are cut away as indicated at 25, so as to lighten the 65 spring plank and increase the convenience of removing the nest of springs, and particularly the center springs 21.

Although I have illustrated and described one particular embodiment of my invention, 70 it will be understood that I do not wish to be limited to the exact construction shown and described, but that various changes and modifications may be made without departing from the spirit and scope of my invention.

I claim:

1. In a truck, a side frame including compression and tension members and a pair of upright columns, said tension member having laterally extending flanges forming an extended support, a spring plank resting on said support, said spring plank having laterally projecting portions between said columns adapted to accommodate a plurality of coil springs, and upright flanges formed along the opposite sides of said spring plank, said flanges being of reduced height along the sides of said widened portions of said spring plank and terminating immediately in front of said widened portions to permit the adjacent springs to be withdrawn forwardly therefrom.

2. In a truck, a side frame including compression and tension members and a pair of 95 upright columns, said tension member having laterally extending flanges forming an extended support, a spring plank resting on said support, said spring plank having laterally projecting portions between said columns 100

adapted to accommodate a plurality of coil springs, and upright flanges formed along the opposite sides of said spring plank, said flanges being of reduced height along the 5 sides of said widened portions of said spring plank and terminating immediately in front of said widened portions to permit the adjacent springs to be withdrawn forwardly therefrom, and the side margins of said 10 spring plank being cut away forwardly of said side flanges.

3. In a truck, a side frame including compression and tension members and a pair of upright columns, said tension member having laterally extending flanges forming an extended support, reinforcing corner ribs formed between the outer margins of said flanges and said upright columns, a spring plank resting on said support between said 20 corner ribs, said spring plank having laterally projecting portions between said columns adapted to accommodate a plurality of coil springs, and upright flanges formed along the opposite sides of said spring plank, said 25 flanges being of reduced height along the sides of said widened portions of said spring plank and terminating immediately in front of said widened portions to permit the adjacent springs to be withdrawn forwardly 30 therefrom.

Signed at Lima, Ohio, this 13th day of May, A. D. 1931.

CLARENCE B. HARBISON.
